UNITED STATES PATENT OFFICE.

WILLIAM D. RICHARDSON, OF SPRINGFIELD, ILLINOIS.

PAVEMENT.

SPECIFICATION forming part of Letters Patent No. 257,613, dated May 9, 1882.

Application filed March 29, 1882. (No model.)

To all whom it may concern:

Be it known that I, WILLIAM D. RICHARDSON, of Springfield, in the county of Sangamon and State of Illinois, have invented a new and useful Improvement in Pavements, which improvement is fully set forth in the following specification.

This invention relates to pavements for the roadways or streets of cities and towns, and has for its object to provide a pavement which shall be easily constructed, durable in use, and capable of being laid in localities where the ordinary paving materials are difficult to procure.

The invention is specially applicable to localities which have a soft and loamy soil, free from sand, and therefore difficult to pack, and which, by reason of its spongy nature and the geological formation of the ground, is at certain seasons of the year saturated with moisture and at others very hard and dry, and upon which, for all these reasons, it is extremely difficult to construct a pavement which will not soon give way in places and present an uneven surface.

In the present invention the pavement is laid so as to be in effect self-sustaining, so as not to be affected by depressions in the soil below, it being laid in the form of an arch, continuous from one curb to the other. It is also made impervious to moisture.

The manner of laying the pavement is as follows: The surface of the road-bed being properly prepared, in the usual manner, by rolling or ramming, and made in the form of an arch, a continuous layer of asphalt or similar material—such as a water-proof cement—is laid from one curb to the other to a depth of from one to three inches. Upon the surface thus formed is placed a layer of brick laid flatwise and as close together as possible. Another similar layer of asphalt or cement is laid above this course of brick. The layer of brick thus enclosed between two layers of cement presents a structure which is practically self-sustaining, as it forms an arch springing from the curbs on each side of the street, and therefore is not liable to be affected injuriously by the yielding nature of the soil below. As the weight to be supported is distributed over a large surface, the pavement being a continuous structure, it is obvious that it can be applied directly to the earth-surface, and that even a very soft and

spongy soil will be capable of sustaining it. Upon the top layer of asphalt or cement is laid the final course of brick, which constitutes the pavement proper. In this layer the bricks are laid sidewise, so that the width of the brick constitutes the thickness of the layer, and, as in the lower course, the bricks are placed close together, so as to leave little or practically no space between them. Such interstices as necessarily remain may be filled with sand, if desired, the sand being spread upon the surface and left to pack itself in the joints.

The invention will be readily understood by reference to the accompanying drawings, which form a part of this specification, and in which—

Figure 1 is a perspective view, and Fig. 2 a vertical cross-section, of a pavement laid in accordance with the invention.

A represents the natural soil or earth upon which the pavement is laid. Its surface is arched from curb to curb and packed by ramming or rolling to render it as hard and solid as the nature of the soil will permit. Upon the surface thus prepared is placed a layer, B, of asphalt or a suitable water-proof cement—such as hydraulic cement. Upon the surface of the asphalt or cement is next laid a flat course of bricks, C, placed in close contact with each other, so as to form a practically-continuous arch from one curb to the other, and preferably laid so as to break joints, as well understood. A second layer, D, of asphalt or cement is now applied to the surface of the course of brick C, and, finally, above it is laid a top course of brick, E. The bricks in course E are laid as in the lower course, so as to make tight joints and to form a continuous arch with the curbs as abutments; but instead of being laid flatwise, the bricks in layer E are placed on their sides—i.e., the thickness of the course or layer will be equal to the width of the individual brick. This completes the pavement so far as concerns its solid structure; but in order to keep the upper surface from abrasion, or to produce a better tread-ing-surface, the pavement may be finished off by a top dressing, say, of tar and coarse sand or gravel; or simply a layer of sand may be spread upon the surface and permitted to work its way into the interstices between the bricks.

It will be readily understood that a pavement thus constructed will form a solid self-

sustaining structure, in which the weight will be distributed over a large surface, and which is therefore independent of the character of the earth foundation, so that although the latter 5 may be liable to inequalities of surface, as from accession of moisture or from other cause, such changes cannot affect the form or durability of the pavement, nor can any moisture penetrate it either from above or below. It will be seen, 10 moreover, that from the nature of the materials employed the pavement is peculiarly adapted to localities where sand, stone, and gravel, which usually enter largely into the construction of pavements, are scarce and costly. 15 The foundation for the final course of brick, which comprises the upper and lower layers of asphalt or cement and the inclosed layer of brick, may be found applicable as a foundation for other than a brick pavement or surface, as 20 it presents a continuous self-sustaining structure and can be applied directly to the earth surface, even where the soil is of a nature to furnish but little support, without the usual foundation of sand, gravel, or crushed rock 25 commonly employed.

Having now fully described my said invention and the manner of carrying the same into effect, what I claim is—

1. A pavement for streets and roadways, comprising brick and asphalt or similar material

in alternate courses, laid in the form of an arch, with the ends resting on the curbstones, substantially as described.

2. A pavement consisting of a bottom layer of asphalt, cement, or similar material, a course 35 of brick, a second layer of asphalt or cement, and a top course of brick, the whole forming an arch, of which the curbstones are the abutments, substantially as described.

3. In a pavement, the combination of the bottom layer of asphalt, cement, or similar material, the intermediate course of brick, laid flatwise and with tight joints, the second layer of asphalt, cement, or similar material, and the top course of brick, laid sidewise, as explained, 40 and also with tight joints, the whole forming an arch, resting on the curbstones, substantially as described.

4. As a foundation for a pavement for streets and roadways, an arched course of brick laid 45 close together and inclosed between two layers of asphalt, cement, or similar material, substantially as described.

In testimony whereof I have signed this specification in the presence of two subscribing witnesses.

W. D. RICHARDSON.
